UNITED STATES PATENT OFFICE

91,529

DESIGN FOR AN OPHTHALMIC MOUNTING

Michael R. McDanal, Denver, Colo.

Application June 27, 1931. Serial No. 40,346

Term of patent 14 years

To all whom it may concern:

Be it known that I, MICHAEL R. McDANAL, a citizen of the United States, residing in the city and county of Denver, State of Colorado, have invented a new, original, and ornamental Design for an Ophthalmic Mounting, of which the following is a specification, reference being had to the accompanying drawing, forming part thereof.

Figure 1 is a front elevation of an ophthalmic mounting showing my new design; and Figure 2 is another front view showing the placement of the temples when folded.

The dominant feature of my design resides in the ornamental effect produced by the positioning of the mountings of the nose-bridge and the temple-bars separately and relatively to each other, said mountings including the strap connecting with the lens.

I claim:

The ornamental design for an ophthalmic mounting, as shown and described.

MICHAEL R. McDANAL.
